UNITED STATES PATENT OFFICE.

HARVEY HUBBELL, OF BRIDGEPORT, CONNECTICUT.

ADVERTISING DEVICE.

1,176,451.

Specification of Letters Patent. Patented Mar. 21, 1916.

Application filed July 29, 1915. Serial No. 42,521.

To all whom it may concern:

Be it known that I, HARVEY HUBBELL, a citizen of the United States, residing at Bridgeport, county of Fairfield, State of Connecticut, have invented an Improvement in Advertising Devices, of which the following is a specification.

This invention has for its object to provide an inexpensive and attractive advertising device in the form of a card, sheet or folder, adapted for use in connection with a number of articles comprising two interchangeable parts adapted for sale singly or in combination, which shall illustrate the articles independently, give catalogue indication, list price, standard package number, &c., of the articles independently, and shall also illustrate combinations of said articles and give catalogue indication, list price, standard package number, &c., of the various combinations likely to be called for by the trade, without the use of movable or interchangeable parts.

With this end in view I have devised the novel advertising device which I will now describe, referring to the accompanying drawing forming a part of this specification, which is a plan view of a portion of the sheet, card or folder and illustrates the principle of the invention.

10 denotes the sheet, card or folder which for convenience I will hereafter call the card, and which may be made of any suitable material, as metal, celluloid or paper.

As a convenient embodiment of my novel invention, I have illustrated it as applied to electrical fixtures, as sockets, switches, rosettes and the various styles of caps therefor, which are standard and interchangeable. By preference, although not necessarily, the face of the card is divided, by equidistant lines crossing each other at right angles, into squares. Across the top of the card is a series of pictures or representations of one set of the interchangeable parts, the parts illustrated in the present instance being different styles of caps for electric fixtures, the series being indicated by 11. Across the left end of the card and at right angles to the other series is a series of pictures or representations of the other set of interchangeable parts, the parts illustrated in the present instance being different styles of electric fixtures and the series being indicated by 12. The rest of the surface of the card bears pictures or representations of

combinations of fixtures and caps, the representations being in vertical columns and in horizontal lines in alinement with the pictures or representations in the two series indicated by 11 and 12. An essential feature of the invention is that at the intersection of an imaginary vertical line extending from any article in series 11 with an imaginary horizontal line extending inward from any article in series 12 is a picture or representation of the two articles combined. For example, at the intersection of a line extending from the cap indicated specifically by *a* with a line extending from the fixture specifically indicated by *b*, is a representation of cap *a* in combination with the fixture *b*.

It will be noted that each cap and each fixture has its own catalogue indication, the catalogue indications of the caps being HA, HB, &c., and of the fixtures 50, 51, &c., the two indications combined forming the catalogue indications, thus: 53—HD indicates the catalogue indication of the combination of fixture 53 with cap HD. Below each fixture or representation, I place the price of each article in cents, as, 23¢ for the article bearing the catalogue number 53, 7¢ for the cap bearing the catalogue indication HD, and 30¢ for the combination bearing the catalogue indication 53—HD. I also place under each article a letter to indicate the schedule, as B, and a number indicating the standard package number, as 500.

Having thus described my invention, I claim:

1. An advertising device for series of articles comprising two interchangeable parts, consisting of a card having across the top a series of representations of one set of the interchangeable parts and across one end at right angles thereto a series of representations of the other set of interchangeable parts, the rest of the surface of the card bearing representations of combinations of articles from the two series, said representations of combinations being so arranged that the representation at the intersection of imaginary lines extending inward from an article in each series will show the two articles combined.

2. An advertising device for series of articles comprising two interchangeable parts, consisting of a card having across the top a series of representations of one set of the interchangeable parts with catalogue indi-

cation, list price and package number, and across one end at right angles thereto a series of representations of the other set of interchangeable parts with catalogue indication, list price and package number, the rest of the surface of the card bearing representations of combinations of articles from the two series with combined catalogue indication, list price and package number,

said representations of combinations being 10 so arranged that the representations at the intersection of imaginary lines extending inward from an article in each series, will show the two articles combined and give catalogue indication, list price and package 15 number of the combination.

In testimony whereof I affix my signature.
HARVEY HUBBELL.
